WASHING-MACHINE.

No. 832,787.

Specification of Letters Patent.

Patented Oct. 9, 1906.

Application filed June 18, 1905. Serial No. 266,077.

To all whom it may concern:

Be it known that we, WILLARD C. FOSTER and LEWIS E. GARRISON, citizens of the United States, and residents of Kalamazoo, 5 in the county of Kalamazoo, State of Michigan, have jointly invented a new and useful Washing-Machine, of which the following is a specification.

The object of this invention is to facilitate 10 the washing of clothes by the forceful contact of hot water against and through the clothes by the means of the improved features of construction herein described and claimed.

15 In the drawings forming a part of this specification, Figure 1 is a side elevation with a portion in section on dotted line *c c* in Fig. 4 and on dotted line *e e* in Fig. 5; Fig. 2, plan of Fig. 1; Fig. 3, an end view of the bottom of Fig. 6; Fig. 4, interior plan of bottom of machine; Fig. 5, plan of Fig. 1 with top and agitator removed; Fig. 6, side elevation of the agitator with rod broken away, and Fig. 7 is a plan of Fig. 6.

25 The parts of the drawings are pointed out by numerals.

The ordinary metal washtub 8 is provided with a cover 9, which cover has a door 10, hinged at 11 and 12 and held closed by but- 30 tons 13 and 14. Through the door 10 the hot water is put in, and the clothes and the agitator 15 are put in and taken out. A rod 16 of the agitator 15 extends up through a bearing-tube 17, attached to the center of the 35 cover 9, and a crank 18 is attached to the upper end of said rod 16 and held by a nut.

It is our purpose to provide the machine with the two following important features: first, hot-air and hot-water spaces within the 40 wall of the tub 8 and circling around the tub interior and separated from the same to prevent the hot water in the machine in which the clothes are being washed from cooling too fast; second, a circular row of flat surfaces at 45 right angles to each other in the interior of the machine, where the washing of clothes is being done, in a manner that the water will be splashed squarely against said flat surfaces by the action of the agitator 15, and 50 from which surfaces said water is reacted back against and through the clothes. We accomplish these two purposes or objects in a cheap and very simple manner by providing

the shell 20 and in the manner of its construction. This shell is metal and hoop or 55 drum like in form and open at top and bottom ends. Its thin wall is bent to form coarse corrugations, which thus appear on both the outer and inner surface of the wall of the shell 20. The size of this corrugated 60 shell is such that it will closely and easily and detachably fit into the tub 8, as in Figs. 1 and 5, the apexes of the outer corrugations just touching the interior of the wall of the tub 8, as in Figs. 1 and 5, and thus establishing a 65 circular row of hot-air and hot-water three-cornered spaces 21 entirely around the tub 8 between its wall and the wall of said corrugated shell 20.

By the touching of all the outer apexes of 70 the corrugations against the inner wall of the tub more room in a given size construction is had for the clothes, the shell is held steady in one position, allowing of no side play and cramping, and the hot-air and hot-water 75 spaces, though separate from and independent of each other, are located very close to each other and have more nearly the effect of a single space around the tub. At the same time by the same construction the inner flat 80 surfaces above described are established, and said surfaces 32, Fig. 5, do not in any sense serve as rubbing-surfaces for the clothes. The clothes are freely tossed forth and back in the water in which they float by the agi- 85 tator 15 in a manner to force the water through the clothes, and thus remove the dirt without wear. The raised portion 19 is for attachment of wringer. The corrugated shell 20 is provided with upper holes 22 and 90 lower holes 23, leading into the spaces 21, through which holes, owing to their small size and fixed location, hot air and steam circulate with more or less force, acting upon the clothes. The shell 20 is easily de- 95 tached for cleaning. The agitator 15 is an important feature, owing to its peculiar construction, by means of which the water is given an upward forward throw, some of it squarely against the inner flat angled sur- 100 faces of the shell 20, from which it reacts forcibly upon the clothes. The body of the agitator is thin and rectangular in form. The upper outer portion of one side at one end, the lower outer portion of the opposite side 105 at the same end, the upper outer portion of

said opposite side at the other end, and the lower outer portion of the first-named side at the latter-named end are all scooped out, as in Figs. 3, 6, and 7. The series of holes 31 through the body of the agitator allow the water to pass through and cause it to operate easier.

To cause the machine to operate easier if overloaded with clothes, we use a supplemental bottom 27, mounted on a central pivot 24 and ball-bearings 25, said pivot 24 loosely fitting a central socket 26 in the bottom of the tub 8. This bottom has downwardly-extending grooves 29, in which are

partitions 30, forming pockets 28 for the balls 25. If care is used to not overload the washing-machine, the supplemental bottom can be dispensed with.

In the operation the supplemental bottom 27 and boiling hot water are placed in the tub 8. The cover 9 is placed on, observing to leave the door 10 open. As the agitator-rod 16 is loose in its bearing-tube 17, it can be moved up and down, so as to handle the door 10 and agitator 15 without disconnecting them. Now place in a few clothes and the agitator 15 and close and fasten door 10. Such soap may be used as desired. Swing the crank forth and back about the distance

one can reach for perhaps ten minutes, or it 30 may be entirely revolved now and then in alternation with the short swinging movement. Run the clothes through the machine more than once, if desired.

Having thus described our invention, what 35 we claim as new, and desire to secure by Letters Patent of the United States of America, is—

In a washing-machine, an outer tub combined with a shell open at top and bottom, 40 and made from a continuous metal band corrugated to form the inner and outer flat surfaces described, said shell adapted to fit detachably into the tub, the outer apexes of its corrugations touching the inner surface of 45 the tub-wall making the three-cornered; separated, independent, hot-air and hot-water spaces closely located end to end to each other around the tub interior, and the small holes near the top and bottom of the shell 50 leading through the same, substantially as set forth.

WILLARD C. FOSTER.
LEWIS E. GARRISON.
